UNITED STATES PATENT OFFICE.

ALFRED STROMBERG, OF CHICAGO, ILLINOIS.

TELEPHONE-RECEIVER.

No. 910,603.

Specification of Letters Patent.

Patented Jan. 26, 1909.

Application filed October 2, 1906. Serial No. 337,082.

To all whom it may concern:

Be it known that I, ALFRED STROMBERG, a citizen of the United States of America, and a resident of Chicago, county of Cook, 5 and State of Illinois, have invented a new and useful Improvement in Telephone-Recievers, of which the following is a specification.

My invention pertains to telephone receivers, and has as its object the production 10 of a receiver in which a predetermined separation is readily and definitely attained between the diaphragm and the magnet pole pieces, and in which also the diaphragm is 15 provided with damping and strengthening means to improve the life and efficiency of the diaphragm.

In my improved receiver, I mount the 20 magnet pole pieces in a metal mounting cup, aline the faces of the pole pieces with the edges of the mounting cup, then place the diaphragm over the edges of the cup with an intervening distance washer of proper thickness to produce proper separation between 25 the center of the diaphragm and the faces of the pole pieces; this distance washer is clamped upon the edge of the diaphragm, thereby becoming a part thereof, and by weighting and strengthening the edges of the 30 diaphragm produces a damping effect in the diaphragm when the receiver is in use, and very greatly strengthens the diaphragm against accidental injury when the receiver is taken apart for inspection or repairs.

In receivers of ordinary construction, 35 where the diaphragm is clamped directly between the shell and the ear piece, the diaphragm is often buckled by the twisting action necessary to bring the ear piece properly upon its seat against the diaphragm. This is particularly true where the face of the shell against which the diaphragm rests is not exactly in a plane or where the diaphragm is not of uniform thickness.

By my invention no twisting action whatever is brought to bear upon the diaphragm proper, and therefore I eliminate the likelihood of a buckled diaphragm which would result in inefficiency in the operation of the 45 receiver.

In the sheet of drawings accompanying this specification, Figure 1 shows a view of my improved receiver with the cap and diaphragm removed; Fig. 2 shows a sectional view of the 55 complete receiver on the line 2 of Fig. 1; and

Fig. 3 shows a sectional view of the complete receiver on the line 3 of Fig. 1.

In constructing the receiver here illustrated, the non-magnetic metal cup 10 is perforated to receive both ends of the permanent magnet 11, and screws 12, 13 and 14; the poles of the permanent magnet 11 are recessed to take the extension pole pieces 15 and 16 respectively, bearing the magnet coils 17 and 18 respectively, the screws 12 and 13 acting with 60 threads in the extension pole pieces 15 and 16 to lock permanent magnet, pole pieces and mounting cup rigidly together. Screw 14 holds in place the insulating block 19, carrying terminals 20 and 21; 22 is an insulating 65 washer adapted to hold the terminal pieces 20 and 21 in alinement and prevent accidental contact with conducting portions of the receiver structure.

The mounting cup, magnet, coils and pole 70 pieces thus assembled are finished by grinding or turning off the edge of the cup 10 and the faces (or outer ends) of the pole pieces 15 and 16, thus bringing the faces of the pole pieces into accurate alinement with the edges 75 of the mounting cup 10. Diaphragm 23 is provided with a rim, flange or distance ring 24, which in assembly is interposed between the face of the diaphragm 23 and the edges of the mounting cup 10 and which thus holds 80 the center of the diaphragm away from the faces of the pole pieces a distance accurately determined by the thickness of the distance ring or washer 24 in that portion of it which lies between the diaphragm and the edges of 85 the mounting cup.

The rubber case, consisting of parts 25 and 26, is placed in position as shown surrounding the parts above described, clamping them firmly together, and giving a desirable outer 90 finish to the receiver as a whole. To further improve the receiver thus constructed, the distance ring 24 is spun over the edge of the diaphragm 23 so that it forms a strengthening member for the diaphragm, and also places 95 the diaphragm under restraint to prevent or subdue the natural vibrations of the diaphragm when vibrated by magnetic variations caused by electric speech currents through the coils 17 and 18.

I do not wish to limit myself to the exact details herein illustrated and described, as I understand that many modifications may be made without departing from the spirit or scope of my invention.

105

110

Having thus described my invention, what I claim as new and desire to secure by United States Letters Patent is:

1. In a telephone receiver, a diaphragm with a reinforced edge, said reinforced edge consisting of a ring of brass spun upon the edge of the diaphragm, substantially as described.
2. In a telephone receiver, a diaphragm with a reinforced edge, said reinforced edge consisting of a ring of metal spun upon the

diaphragm and forming a reinforcing ring upon each side of the diaphragm, substantially as described.

Signed by me at Chicago, county of Cook, 15 and State of Illinois, in the presence of two witnesses.

ALFRED STROMBERG.

Witnesses:

DAVID S. HULFISH,
HARRIET L. SMITH.
